UNITED STATES PATENT OFFICE

JOHN A. WIENER, OF LAUREL, MISSISSIPPI, ASSIGNOR TO MASONITE CORPORATION, OF LAUREL, MISSISSIPPI, A CORPORATION OF DELAWARE

METHOD AND APPARATUS OF FORMING THICK SHEETS FROM PULP

Application filed May 24, 1927. Serial No. 193,821.

This invention relates to the manufacture of composition boards, sheets, plates, and similar articles, which are adapted for use as sound and heat insulating linings, 5 wall boards, artificial lumber, or other structural elements. In particular it relates to the manufacture of such articles from a liquid cellulose or wood fibre pulp, which is flowed into a sheet, dried and compressed and 10 cut into suitable lengths.

The principal object of my invention is to provide an improved method and apparatus for compressing the flowed sheet of pulp, and extracting the water therefrom.

15 In the embodiment of the invention herein disclosed, the sheet is formed by flowing the liquid pulp onto the traveling screen of a Fourdrinier machine. The screen carries the sheet over a suction box and then between pressure rolls, by means of which much 20 of the water is extracted from the pulp mass, and the sheet is compressed.

In the present invention, I operate the suction box under a partial vacuum, and the 25 pulp sheet, as it travels over the suction box, is covered by an apron of material, which travels with the sheet in contact with its upper surface, and which is substantially impervious to passage of air, and the term impervious is used in this sense in my claims. The effect of the suction acting on the bottom 30 of the sheet through the screen, together with the apron which covers the top surface of the sheet, is to cause the sheet to be progressively, gradually and evenly compressed between the screen and apron. In this manner a large part of the water is squeezed out of the pulp, and the pulp is compressed to a homogeneous sheet or board of uniform thickness. 35 The sheet is then further compressed, cut into suitable lengths, and otherwise finished as desired.

The apron which covers the sheet as it 40 passes over the suction box is preferably in the form of an endless belt, formed of rubberized fabric or similar flexible material. The apron belt is mounted above the pulp sheet, and its lower course travels with and over the screen, being guided so 45 that during the first part of its movement

over the suction box it is in close sealing contact with the top surface of the pulp sheet. During the latter part of its movement over the suction box, and while the pulp sheet is still tightly held down 55 against the screen by the suction, the apron is guided upwardly away from the sheet. In this manner I secure the breaking away of the apron from the sheet without lifting the sheet from the traveling screen or otherwise disturbing or injuring the sheet.

There is a strong tendency to draw the screen and sheet down into the suction box. To prevent this, I provide special means for firmly supporting the screen as it travels 60 over the mouth of the suction box. In the form of invention herein disclosed such means consists of an endless carrier, located in the suction box, immediately below the screen. The carrier extends the full width and length 65 of the mouth of the suction box and throughout its length is in supporting contact with the bottom of the screen. The screen and carrier move together, and I preferably employ 70 a separate driving means for the carrier, so that the carrier, acting through its supporting contact with the screen, assists in driving the screen over the mouth of the suction box.

The suction box which I employ is specially constructed to withstand the atmospheric 75 pressure to which it is subjected.

Numerous other advantages and objects of my invention will appear from the following description taken in connection with the accompanying drawings.

Fig. 1 is a side elevation, partly in section and partly broken away, of a Fourdrinier machine embodying one form of my invention.

Fig. 2 is a schematic top plan view of one side of the machine shown in Fig. 1, with the deckle wheels removed.

Fig. 3 is an enlarged longitudinal sectional view of the suction box shown in Fig. 1.

Fig. 4 is a section taken on the line 4—4 of Fig. 1, and

Fig. 5 is an enlarged detail sectional view of a portion of the structure shown in Fig. 4, indicated by the arrow 5 in Fig. 4.

The wood or other fibrous stock used in 100

making the pulp is disintegrated by any suitable means, preferably by exploding the stock in the manner described in United States Patent No. 1,578,609, granted on 5 March 30, 1926 to William H. Mason. The mass of loose fibres formed in this manner is mixed with water to form a liquid pulp, and this is fed through a spout 9, shown at the right of Fig. 1, into an agitating tank 10 that 10 is provided with vertical baffles or partitions 11, 12 and 13. The pulp passes through the tank 10, flowing up and down, under baffles 11 and 13 and over baffle 12, and is delivered from the tank 10, through an opening 16, 15 into a trough 18. Between the bottoms of the baffles 11 and 13 and the bottom of the tank 10 are rotating hollow perforated cylinders 17, which act in a manner well known in the art to agitate the pulp, and make it of 20 uniform consistency.

Trough 18 has a flat bottom 19, and side plates 20, preferably formed of thin brass. The bottom of trough 18 terminates at a point indicated by 22 in Fig. 1, and at this point 25 the pulp passes to a traveling endless screen 26, which carries the pulp over the table rolls 27, thence carries the pulp in the form of a sheet 28 over the mouth of the suction box 30, over the table rolls 32, and under the 30 screen tightening roll 33, and finally between the upper and lower rolls of pairs of press rolls indicated at 35.

From this point the pulp sheet 28, which has been considerably pressed and freed 35 from water, passes on to a cutting machine, not shown, and the carrier screen 26 passes down around the last of the lower press rolls 35, and thence back to the breast roll 37.

Press rolls 35 and breast rolls 37 are both 40 driven from a suitable source of power, not shown, and these rolls form part of the driving means for the carrier screen 26. Adjustable idle rollers 38, serve to maintain the carrier screen 26 under proper tension.

45 The sides 20 of the trough 18 extend beyond the point 22, at which the bottom of the trough terminates, to a point 40 (Fig. 1) approximately midway of the length of suction box 30, and the carrier screen 26 extends 50 laterally under the extended side plates 20, which thus form a means for preventing the pulp from flowing off the edges of the screen.

Beyond the forward ends of the side plates 55 20 the pulp is retained on the screen by deckle straps 42, which move with the screen 26, resting on the margins of the screen 26, as indicated in Fig. 5, which shows the margins of the screen 26 resting on the top of the side wall of the suction box, and a deckle strap 42 60 supported on the margin of the screen.

The deckle straps 42, which are endless rubber belts, pass around wheels 44 and 45, and as shown in Fig. 2, these deckle straps are located outside plates 20 of the trough 65 18. The deckle straps assist plates 20 in pre-

venting the pulp from flowing off the edges of the screen, and beyond plates 20 the deckle straps support the pulp sheet at each of its edges, and form an air seal in conjunction with apron 46, which is received between 70 the deckle straps.

Moving into contact with the upper surface of the pulp sheet as it moves over the mouth of the suction box, is an endless apron 46, formed of impervious, or in other words air-tight, material, such as rubberized fabric, which preferably has a smooth outer surface. The apron 46 passes over upper rolls 48 and 49 (one or both of which may be a tightener roll), thence down around roll 50, at which point it moves into contact with the pulp. It then travels with the pulp to roll 51, which is located somewhat below roll 50, so as to guide the apron 46 in such a way that it will remain in contact with the pulp sheet as the sheet becomes progressively thinner under the suction from the suction box 30. 85

From roll 51 apron 46 passes upward at a slight incline away from the screen 26 and pulp sheet 28. Beyond the roll 51 the 90 apron leaves the upper surface of the pulp sheet 28, and passes under and around roll 52. The pulp sheet is at this time still tightly held by the suction against the carrier screen 26, and the breaking away of the apron from the pulp sheet is effected without raising or disturbing the sheet. 95

From roll 52 the apron 46 passes back to upper roll 48. One or both of rolls 48, 49 may be adjustable to regulate the tension 100 of the apron 46.

I may, if desired, provide separate driving means for the apron 46. I find, however, that the apron may be satisfactorily driven from the moving pulp sheet through the frictional, sealing surface engagement between the apron and sheet, the apron being held forcibly down on the moving sheet by the partial vacuum in suction box 30. 105

The suction box 30, which is built to withstand a high vacuum, has sides formed of L-shaped metal members 60, shown in section in Figs. 4 and 5. Said side members 60 are preferably formed with broad upper flanges 60' to form trackways for the outer edges of screen 26 and the deckle straps 42. The ends of the box 30 are semi-cylindrical and are welded to the sides 60 and to the bottom 62. The bottom 62 is formed of metal plates which are reinforced by longitudinal T-bars 63. The metal plates are welded to the sides and the ends of the box and incline downwardly, as shown in Figs. 1 and 3, to a sump or trough 64, formed of a pipe 65, part of which has been cut away, and the cut edges welded to the bottom plates and sides. 115

The remainder or uncut portions of the pipe 65 extend outwardly at opposite sides 120 of the suction box 30 and form passages com- 125

5 municating with a suction pump not shown. By employing suction passages at opposite sides of the suction box, an equal amount of suction is created at both sides of the center of the pulp sheet. One or more hand-holes 30', suitably closed with hand-hole plates, may be provided to give access to the interior of suction box 30 when desired.

10 In practice, I operate the suction box under a vacuum of, for example, three inches or more mercury. As the mouth of the suction box in certain machines is approximately four feet wide and nine feet long, the suction creates an enormous downward pressure on the screen and pulp sheet, tending to draw them into the suction box. To prevent this, I provide a means for supporting the screen and pulp sheet as they pass over the suction box.

20 Such supporting means comprises an endless carrier or conveyor which is very stiff and strong in its crosswise direction and at the same time flexible in the longitudinal direction, so that it is adapted to run on 25 sprocket wheels or the like. In the present form of my invention this means comprises an endless carrier 67, mounted in the suction box. This carrier comprises two series 30 of sprocket wheels 68, mounted on parallel transverse shafts 70 and 71, journaled in the sides of the suction box 30. The carrier is driven at the same rate as the Fourdrinier screen in order to obviate slippage relative thereto. As shown, its shaft 70 is driven from 35 a sprocket wheel 73, which in turn derives its motion from a source of power, not shown. Passing over the sprocket wheels 68 on the shafts 70 and 71 are a series of endless chains 75, spaced from one another as indicated in Fig. 4. The chains are connected by spaced 40 transverse carrier bars 76, each of which is secured to a link of each chain by two L-shaped brackets 78, which are secured to opposite sides of each link. The bars 76 45 are formed with cylindrical outer surfaces, and the top bars of the carrier move with the screen 26 and bear against the bottom of the screen, thereby supporting the screen as it moves over the mouth of the suction box. 50 As the carrier 67 is separately driven, the carrier, through its supporting contact with the screen, may act as a driving means for the screen.

55 The upper course of the carrier, as it travels with the screen, is supported by longitudinally extending metal T-shaped members 80, which in turn are supported by a series of transverse bars or beams 81, carried at their ends by members 82 secured to the sides of 60 the suction box. The T-shaped members 80 extend upwardly into contact with the bottoms of the carrier chains 75; the links of the chains 75 being provided with rollers 75a, running on the tops of the members 80 65 as the chain moves.

Roll 51 and suction box 30 and parts carried thereby are preferably supported on a concrete foundation, shown at 84 in Fig. 4.

70 On leaving the suction box 30, the pulp sheet is carried by the screen 26 over the table rolls 32 and between the press rolls 35, of which a plurality of pairs, preferably three pairs, are provided. In this part of its travel, the sheet 28 is carried on screen 26 and under the screen belt 83, which runs under the upper set of press rolls 35 and over idler roll 84 and the adjustable tightener roll 33. Roll 33 can also be raised and lowered by the adjusting screw 85 so as to bring screen belt 83 into engagement with the pulp sheet gradually in 75 the course of the reach of said screen belt 83 between tightener roll 33 and the first roll of press rolls 35. The pressure of rolls 35 can be controlled by the adjustment of weights 86 along lever arms 87, the arms 87 80 being connected with the upper press rolls through rods 88 and removable roll mountings 89.

85 I claim:

1. The method of forming a homogeneous 90 pressed sheet from liquid pulp supported on a flat wire screen, which comprises covering the top of the pulp with an impervious apron, supported to permit its vertical movement, and exhausting air from beneath said wire screen, whereby said pulp is squeezed between said apron and screen, and water is forced out of said pulp.

95 2. The method of forming a homogeneous 100 pressed sheet from liquid fibre pulp, which comprises flowing the pulp onto a flat wire screen, covering the top of the flowed pulp with an impervious apron supported so as to permit its vertical movement, and exhausting the air from beneath said screen, whereby the pulp is tightly squeezed between the apron and screen and water is forced out of 105 said pulp.

110 3. The method of forming a homogeneous pressed sheet from liquid pulp, which comprises flowing the pulp onto a flat wire screen, covering the top of the flowed pulp with an apron of impervious flexible material, exhausting air under partial vacuum from beneath said screen, whereby, due to the suction created, the pulp is tightly squeezed between the screen and apron, and removing said apron from said pulp sheet, progressively along said sheet, while the sheet is still held against the screen by the suction.

115 4. The method of forming a homogeneous 120 pressed sheet from liquid pulp, which comprises flowing the pulp onto a flat wire screen, covering the top of the flowed pulp with an apron of impervious flexible material, having a smooth lower surface, exhausting air under partial vacuum from beneath said screen, whereby, due to the suction created, the pulp is tightly squeezed between 125 said screen and apron, and removing said 130

apron from the pulp sheet, progressively along said sheet, while the sheet is still held against the screen by said suction.

5. An apparatus for forming a pressed sheet from wet pulp, comprising a traveling carrier screen, means for feeding soft wet pulp onto said screen, an impervious apron movable onto said pulp on said screen, and movable with said pulp and screen, a suction box located beneath said screen and apron, and means for exhausting air from said suction box, whereby said pulp is compressed between said apron and screen.

10. An apparatus for forming a sheet from wet fibrous pulp, comprising an endless carrier screen, means for feeding soft wet pulp onto said screen, a suction box located beneath said screen, and an endless apron of impervious material, movable downwardly into contact with the upper surface of said pulp, and thence with said pulp as it is moved by said screen above the mouth of said suction box, and means for exhausting air from said suction box, whereby said pulp is compressed between said apron and screen.

15. An apparatus for forming a pressed sheet from wet pulp, comprising a screen upon which said pulp is supported, an impervious apron supported in contact with the upper surface of said pulp, and means for exhausting air from beneath said screen, whereby the pulp is compressed between said apron and screen.

20. An apparatus for forming a sheet from wet fibrous pulp, comprising an endless carrier screen, means for feeding soft wet pulp onto said screen, a suction box located beneath said screen, and an endless apron of impervious material, movable downwardly into contact with the upper surface of said pulp, and thence with said pulp as it is moved by said screen above the mouth of said suction box, and means for exhausting air from said suction box, whereby said pulp is compressed between said apron and screen, said apron, as it moves with said pulp, being guided towards said screen so that it remains into contact with said pulp as the sheet of pulp becomes progressively thinner under said compression.

25. An apparatus for forming a sheet from wet pulp, comprising an endless carrier screen, means for feeding soft wet pulp onto said screen, a suction box located beneath said screen, and an endless apron of impervious material movable downwardly into contact with the upper surface of said pulp, thence with said pulp as it moves part of the distance across the mouth of said suction box, and thence upwardly away from contact with said pulp, and means for exhausting air from said suction box, whereby during the initial movement of the pulp over the suction box the pulp is compressed between said apron and screen, and the apron is then withdrawn

from the pulp while the pulp is held on the screen by the suction from said suction box.

30. An apparatus for forming a sheet from wet pulp, comprising an endless carrier screen, means for feeding soft wet pulp onto said screen, a suction box located beneath said screen, an endless apron of impervious material movable downwardly into contact with the upper surface of said pulp, and thence with said pulp as it moves above the mouth of said suction box, whereby said pulp is compressed between said apron and screen, and means on the edges of the pulp sheet for retaining the pulp on the screen, said apron and said last-named means co-operating to form a seal to prevent access of air to said suction box.

35. An apparatus for forming a sheet from wet pulp, comprising an endless carrier screen, means for feeding soft wet pulp onto said screen, a suction box located beneath said screen, an endless apron of impervious material movable downwardly into contact with the upper surface of said pulp, and thence with said pulp as it is moved by said screen above the mouth of said suction box, means for exhausting air from said suction box whereby said pulp is compressed between said apron and screen, and deckle straps supported on said screen at its margins, and movable with said screen, said deckle straps serving to retain said pulp on said screen, and co-operating with said apron to prevent access of air to said suction box.

40. The combination with an endless forming screen of a Fourdrinier machine, means at one end thereof for flowing fibre thereon in a thick sheet and a suction box cooperating with said screen at an intermediate point thereof for withdrawing water therefrom, of a plurality of pairs of oppositely disposed press rolls receiving said screen therebetween beyond the suction box and through which the sheet is passed while still supported by said endless forming screen, and a second endless screen interposed between the top of the sheet and the top pressure rolls.

45. The method of forming a homogeneous sheet of low water content from liquid pulp, which consists of carrying the liquid pulp on a traveling support pervious-to-air-and-water, covering the liquid pulp with a traveling, impervious-to-air apron, and exhausting air from beneath said support whereby water is withdrawn from the pulp.

50. The combination with an endless forming screen of a Fourdrinier machine, means at one end thereof for flowing fibre thereon in a thick sheet and a suction box cooperating with said screen at an intermediate point thereof for withdrawing water therefrom, of a pair of oppositely disposed press rolls receiving said screen therebetween beyond the suction box and through which the sheet is passed and by which the same is positively

pressed while still supported by said endless forming screen, and a second endless screen interposed between the top of the sheet and the top pressure roll.

5 15. The combination with an endless forming screen of a Fourdrinier machine, means at one end thereof for flowing fiber thereon in a thick sheet, of a pair of oppositely disposed pressure rolls receiving said screen 10 therebetween and through which the sheet is passed while still supported by said endless forming screen, the top pressure roll being weighted and freely movable towards the lower roll to exert a pressure upon said sheet, 15 and an endless belt interposed between the top of the sheet and the top pressure roll.

16. The combination with the endless forming screen of a Fourdrinier machine and means for forming a thick pulp sheet there- 20 on, of a pair of pressure rolls, the lower roll of said pair being encircled by said forming screen, and an endless belt encircling the upper roll of said pair, the sheet being inter- posed between said forming screen and said 25 belt while passing between said pressure rolls.

17. The combination with the endless forming screen of a Fourdrinier machine and means for forming a thick pulp sheet thereon, of a pair of pressure rolls, the lower roll of 30 said pair being encircled by said forming screen and an endless belt moving toward said forming screen with a gradual approach and encircling the upper roll of said pair, the sheet being interposed between said forming 35 screen and said belt while passing between said pressure rolls.

18. The combination with the endless forming screen of a Fourdrinier machine and means for forming a thick pulp sheet there- 40 on, of a pair of pressure rolls, the lower roll of said pair being encircled by said forming screen, and an endless belt encircling the upper roll of said pair, the sheet being inter- posed between said forming screen and said 45 belt while passing between said pressure rolls, and means for varying the angle at which said belt approaches the forming screen.

19. The combination with the endless forming screen of a Fourdrinier machine and means for forming a thick pulp sheet thereof, of a pair of pressure rolls, the lower roll of 50 said pair being encircled by said forming screen, and a second endless screen encircling the upper roll of said pair, the sheet being inter- 55 posed between said forming screen and said second screen while passing between said pressure rolls.

In testimony whereof, I have signed my
60 name hereto.

JOHN A. WIENER.
